JOHN W. DENNIS, OF PHILADELPHIA, PENNSYLVANIA, ASSIGNOR TO THE PHILADELPHIA DRYING MACHINERY COMPANY, OF PHILADELPHIA, PENNSYLVANIA, A CORPORATION OF PENNSYLVANIA

FORM FOR DRYING HOSIERY AND THE LIKE

Application filed April 19, 1929. Serial No. 356,414.

This invention relates to forms useful in drying and shaping articles of textile manufacture such as hosiery and the like.

The object of my invention is to provide a drying and shaping form of the kind referred to capable of adapting itself to the article which is to be dried to the advantage that the form may be employed in drying like articles varying in size, for example, stockings with 10 feet of different lengths.

How the foregoing desideratum can be conveniently attained in practice will be manifest from the detailed description following of the typical embodiment of this invention, shown in the accompanying drawing; whereof, Fig. I is a fragmentary view of my improved drying form.

Fig. II is a fragmentary view, on a larger scale, showing a section through the medial 20 plane of the structure.

Fig. III is an edge elevation, viewed in the direction of the arrows III—III in Fig. II; and,

Fig. IV is a transverse sectional view, taken 25 as indicated by the arrows IV—IV in Fig. II.

As herein depicted, the form of my invention comprises a thin flat hollow profile body 5 of metal, which, in the present instance, is suitably configured for shaping and drying 30 long or ladies' hosiery. At the heel and ankle region, the body 5 affords an edge slot 6 which is occupied by an extensible elbow portion 8 or heel piece 7, having pivotal connection 9 in the ankle region. This extensible piece 7 is 35 yieldingly urged outward through the edge slot 6, by a spring 9 with its upper end normally engaging an abutment 10 in said slot. The extensible piece 7 is thus afforded capacity 40 for yielding to depression into the edge slot 6 as a stocking is drawn over the form, thereby automatically adapting the latter to the stocking and enabling use of the form for shaping 45 and drying stockings of different sizes, i. e. stockings having different foot lengths.

The body 5 may be constructed in any convenient manner, for example through uniting two pre-shaped oppositely dished side wall members 5a, 5b of sheet metal as by welding the abutting edges of such members, 50 as at 11 in Figs. II and IV. The isolated

edge slot 6 for the extensible heel piece 7 may be formed through incident placement between the body side members 5, of a partitioning strip 12 which is preferably incorporated in the structure, likewise by welding it at the ends, as at 13 in Fig. II, and along the sides, as at 14 in Fig. IV. As shown in Fig. II, the partitioning strip 12 is recessed at 15 to receive the pivotal end of the extensible heel piece 7, and the form apertured transversely at the designated locality for passage of a flush headed pivot rivet or screw 16. For convenience, I permanently attach the spring 9 to the extensible heel piece 7 as by welding or swaging the laterally turned end 17 of one of its legs into a notch 18 in said heel piece. To insure against lateral flexure and more effective functioning of the free arm of the spring 9, I provide a guide groove 19 for it in the partitioning strip 12, see Figs. 55 II and IV. This construction and arrangement is obviously conducive to economic manufacture of the form, and, moreover facilitates assembling.

The form may be heated internally by steam or hot water, or by an electric heating element placed within its hollow body as desired, or found most convenient, in practice.

It is to be expressly understood that, within the scope of my invention, yielding extensible provisions may be made in regions other than at the heel of a stocking form such as herein exemplified; nor is said invention 80 to be regarded as limited to hosiery drying and shaping forms alone.

Having thus described my invention, I claim:

1. A hosiery drying form comprising a profile body, and a pivoted spring influenced heel piece projecting outward through an edge slot of the body, said heel piece being restrained as regards outward movement by an abutment in the slot but having capacity 95 for yielding as a stocking is drawn over the form thereby to automatically adapt the latter to the stocking.

2. A hosiery drying form comprising a profile body, a heel piece pivoted at the ankle 100

region for limited projection outward through an edge slot of the body, a U-shaped spring having one leg secured to the heel piece and the other engaging a guide groove in the form for capacity to yield as a stocking is drawn over said form and thereby to automatically adapt the latter to the stocking.

5 In testimony whereof, I have hereunto signed my name at Philadelphia, Pennsylvania, this 13th day of April, 1929.

JOHN W. DENNIS.
